UNITED STATES PATENT OFFICE

HOWARD K. KING, OF PHILADELPHIA, PENNSYLVANIA, ASSIGNOR TO CHAMBERS BROTHERS COMPANY, A CORPORATION OF PENNSYLVANIA

AIR PRESSURE DRY PAN

Application filed August 29, 1931. Serial No. 560,136.

The invention relates to improvements in air pressure dry pans.

The object is to provide improved means for increasing or decreasing the pressure of 5 the muller rollers.

Dry pans heretofore in common use were equipped with muller rollers which depended for their crushing pressure solely or chiefly upon the weight of the rollers, and afterwards various means were employed for 10 augmenting or increasing said crushing pressure beyond that due to their weight. In this way the size and weight of the rollers could be reduced while maintaining the desired maximum crushing pressure.

It has been found however that in operating upon certain materials, the mullers now in common use exert a crushing pressure, due to their weight alone, which grind 20 the material more than is desirable, that is the material is liable to be reduced to a fine powder whereas it should only be reduced to a granular condition.

It has been found that by resiliently supporting said rolls so that they will exert a crushing pressure which is due to a part only of their gravity weight the same may be exactly adapted to the particular material operated upon and that the desired character 25 of the product may be secured. This lightening of the rollers may be secured through a desired range of pressures. By combining such means, with adjustable means for augmenting the normal crushing 30 pressure of the rollers due to their weight, a wide range of crushing pressures may be secured, to suit materials and products of substantially different characteristics.

Referring to the drawings, which illustrate merely by way of example, suitable means for affecting the invention:—

Fig. 1 is a front elevation.

Fig. 2 is a vertical section on line 2, 2 of 40 Fig. 1.

Fig. 3 is a horizontal section on line 3, 3 of Fig. 2.

Fig. 4 is a horizontal section on line 4, 4 of Fig. 2.

Fig. 5 is a section, on an enlarged scale, 45 on line 5, 5 of Fig. 4.

Fig. 6 is a section on a still larger scale of the vented check valve.

Similar numerals refer to similar parts throughout the several views.

In the present example two muller rollers 55 8 are used, each roller mounted on an axle 12 which is supported in bearings formed in the two arms of yoke 9 journaled on the shaft 10. The outer ends 11 of the arms of the yoke 9 extend beyond the axle 12 and are pivotally 60 connected as at 14, by adjustable turnbuckles 15, or the like, directly to a piston rod 16. Each piston rod 16 is connected to piston 18 operating in a cylinder 19. Each cylinder 19 is hung by a pair of lugs 20 upon a supporting pin 21 so as to have a slight rocking movement thereon to accommodate the slight arcuate movement of the lower end of its piston rod which is attached to a rock yoke. 65 The pin 21 is attached to a substantial supporting frame 35.

As each arm of each yoke, in the present example, is connected to a piston rod, it will be understood that the crushing pressure of 70 each roller is controlled by two cylinders. 75

It will however be obvious that, in some cases a single arm of each yoke may be connected to a piston rod, in which case a roller may be controlled by a single cylinder.

The general construction, above described, 80 is shown in my copending application filed Nov. 14, 1930, Serial No. 495,682.

The present invention comprises improved means for communicating varying pressures to either side of each piston, whereby the crushing pressure exerted by the rollers may be controlled so as to have a value either greater or less than that exerted by gravity due to the weight of the roller only.

In accordance therefore with the present invention, a pipe 22 is connected to a source of air pressure not shown; it being understood that this air pressure, or the pressure of any suitable compressed elastic fluid medium, may be maintained at any desired value 85 or may be changed from time to time to suit existent conditions. Pipe 22 is connected, through suitable hand valves 23 and 24 to piping 25 delivering to the upper ends of the cylinders, and to piping 26 delivering to the 90 100

lower ends of the cylinders. A hand valve 27 is provided for establishing communication between the upper ends of cylinders and the outside atmosphere, while a hand valve 28 is provided for establishing communication between the lower ends of cylinders and the outside atmosphere.

6 The piping 25 is connected to the upper ends of the cylinders through check valves 29. This system of piping is also provided with pop safety valves 30.

10 The piping 26 is connected to the lower ends of the cylinders through vented check valves 31 provided with a permanently opened vent 32 shown in detail in Fig. 6. The 15 piping system 26 may also include sections 33 of flexible rubber steam hose or other suitable means for permitting slight movement of the cylinders. The piping 22 connected 20 with the compressor or other source of compressed elastic medium, is provided with the usual pressure gage 34 and also with an adjustable reducing valve 35.

In operation:

25 When it is desired to augment the crushing pressure exerted by the rollers, valves 23 and 28 are opened, while valves 24 and 27 are closed. This permits compressed elastic fluid medium to enter the upper parts of the cylinders, to exert downward pressure on pistons 18, while air is permitted to enter and escape through vented check valves 31 and valve 28.

30 When the roller encounters an obstruction, such as a hard lump, it is usually given an upward movement, causing an upward movement of the piston connected thereto; in which case the valve 31 opens to permit the free passage of air into the cylinder beneath the piston. When the roller passes or overcomes the obstruction, it falls thereby causing a downward movement of the piston connected thereto; in such case the air beneath the piston can only escape through the vent 32 in valve 31. As this is a restricted vent, 40 the air may be compressed to a certain extent before escaping, thus cushioning the said downward movement of piston and roller.

45 It will also be understood that when the roller is caused to rise as above described, its crushing pressure is temporarily increased by trapping and compressing the compressed elastic fluid medium above the piston. This is due to the action of the check valve 29; any undue pressure being relieved by the pop safety valve 30. When it is desired to lighten the rollers, that is, to secure a crushing pressure less than that normally exerted by the weight of the rollers, valves 24 and 27, are opened while valves 23 and 28 are closed. 50 This permits compressed elastic medium to enter the lower ends of the cylinders to exert pressure upon the undersides of the pistons and thus reduce the crushing pressure exerted by the rollers.

55 60 65 When the crushing pressure of the rollers

is thus reduced, it is especially important, upon a roller encountering an obstruction, such as a hard lump, that its crushing pressure be temporarily increased. This increase of pressure is secured by trapping the air in the cylinder above the piston by means of check valve 29 so that as the piston rises the crushing pressure of the roller is increased.

70 75 In this way, while the desired character of the product is secured, the efficiency of the device to deal with hard lumps is not impaired.

80 By regulating the pressure of the compressed elastic fluid medium introduced into the cylinders either above or below the piston, a wide range of adjustment is secured of the crushing pressure of the rollers, either above or below that exerted by gravity due to the weight alone of said rollers. This regulation of pressure of the compressed elastic fluid medium admitted to the cylinders is secured by the adjustable reducing valve 35, or other suitable means.

85 What I claim is:—

90 95 1. In a device of the character described, means, having a substantial range of adjustment, for determining the crushing power of the roller from below that exerted due to gravity to above that due to gravity, comprising a movable roller bearing, a cylinder 100 having a piston operating therein, means establishing operative relationship between the piston and the bearing, means for connecting the cylinder on each side of the piston with a source of compressed elastic medium, and means for controlling the delivery of the medium to either end of the cylinder as required.

105 110 2. In a device of the character described, means, having a substantial range of adjustment, for determining the crushing power of the roller from below that exerted due to gravity to above that due to gravity, comprising a movable roller bearing, a cylinder 115 having a piston operating therein, means establishing operative relationship between the piston and the bearing, means for connecting the cylinder on each side of the piston with a source of compressed elastic medium, means for adjusting the amount of said pressure, and means for controlling the delivery of the medium to either end of the cylinder as required.

120 125 3. In a device of the character described, means, having a substantial range of adjustment, for determining the crushing power of the roller from below that exerted due to gravity to above that due to gravity, comprising a movable roller bearing, a cylinder provided with suitable check valves and having a piston operating therein, means establishing operative relationship between the piston and the bearing, means for connecting the cylinder on each side of the piston with a source of compressed elastic medium, and 130

means for controlling the delivery of the medium to either end of the cylinder as required.

4. In a device of the character described, 5 means, having a substantial range of adjustment, for determining the crushing power of the roller from below that exerted due to gravity to above that due to gravity, comprising a movable roller bearing, a cylinder 10 having a piston operating therein, means establishing operative relationship between the piston and the bearing, means for connecting the cylinder on each side of the piston with a source of compressed elastic medium, and 15 means for controlling the delivery of the medium to either end of the cylinder as required, said cylinder also provided with a suitably positioned restricted vent for co-operation with the piston in first retarding 20 and then arresting the downward movement of the roller.
